UNITED STATES PATENT OFFICE.

FRIEDRICH FUCHS, OF ZOFINGEN, SWITZERLAND.

DEVICE FOR REGULATING THE TENSION OF PAPER WEBS.

Application filed May 14, 1927, Serial No. 191,435, and in Switzerland April 7, 1927.

The present invention relates to improvements in devices for regulating the tension and particularly for automatically maintaining constant the tension in a web of paper to be printed.

With webs of paper to be printed variations in the tension of the web occur almost continuously, which may be caused from various reasons, for instance by the irregular 10 braking action of the brake band on the brake pulley on the axle of the roll of paper, or by the reduction in the diameter of the roll of paper during the unwinding, or by a difference in the tightness of the winding 15 of the paper roll itself. Particularly the last two conditions render it impossible to obtain a totally uniform tension of the web solely by the actuation of a brake device, when this actuation is left to the discretion 20 of the attendant.

The known unwinding device, in which the roll of paper is so driven by a wide belt that the speed of the web corresponds to the circumferential speed of the printing cylinders, does not permit to maintain the tension of the web sufficiently uniform as is for instance required for avoiding the differences in the register with multi-color printing, as with the smallest variation in its tension 25 the web stretches or shrinks which obviously causes differences in the register. Further experience has shown that in multicolor printing the principal variations in the register are due to the continuously occurring 30 variations in the tension of the web so that overcoming these variations in the tension permits at the same time multicolor printing with rotary presses.

It is therefore the object of the present 40 invention to provide an arrangement by means of which the tension of the web is automatically maintained constant.

The arrangement according to the present invention comprises a movably mounted device over which the web slides and which is provided with means adapted to hold the device in a determined position for determined tensions of the web, further controlling means are provided which respond to a variation 45 of the position of the device caused by a variation of the tension and which actuate braking means acting on the paper roll in such a manner that the variation of the tension is counteracted.

50 The device is preferably constructed as a

rotatably mounted drum to which an arm is fixed carrying a sliding weight by the adjustment of which the drum is held in a determined position which corresponds to a determined tension of the web.

60

A constructional example of the subject matter of the present invention is illustrated on the accompanying drawings, in which:

Fig. 1 shows in elevation part of a multi-color rotary printing press, having the arrangement for automatically maintaining constant the tension of the web fitted thereto, and the diagram of the electric connections,

Fig. 2 is an axial section of the regulating drum,

70

Fig. 3 shows in an end view the drum and the arm fixed to the latter,

Fig. 4 shows in a plan view the pointed end of the arm,

Figs. 5 and 6 show in front and side elevation respectively with parts shown in section the means for actuating the brake of the paper roll,

75

Figs. 7 and 8 show in front elevation and in a vertical section respectively a detail of the controlling device, and

80

Fig. 9 is an end view of the support of the paper roll showing the brake for the latter.

The web 1 is unwound from the roll of paper 2 and runs over the guide rollers 3, 4 and 5 to the first printing mechanism A and from the latter over the drying drum 6 and guide rollers 7, 8 and 9 and slides over the regulating drum 10 and from there runs over the guide rollers 11 and 12 to the second printing mechanism B and from there for instance to further printing mechanisms not illustrated. The drive of the printing mechanisms is effected by an electric motor 13 through the interposition of a number of gear wheels 14.

85

The regulating drum 10 is rotatably mounted in ball bearings 15 and 16 provided in the parts 17 of the side shields of the printing press. The axle 18 of the drum extends beyond the part 17 of the frame and on this axle an arm 19 is fixed. Along the arm 19 a sliding weight 20 is displaceable and is so adjusted that the arm remains in a determined position, for instance pointing towards the zero-point of the scale 21 provided on the frame part 17 (Fig. 1), whereby the turning moment of the sliding weight 20 and of the arm 19 balances the friction

100

105

110

action of the web on the surface of the drum tending to turn the drum with a determined tension of the web. When this tension changes this state of equilibrium is disturbed 5 and the arm 19 deflects in the upward or in the downward direction.

In order to counteract immediately any alteration of the tension the deflection of the arm is utilized to actuate the brake on 10 the paper roll 2. The brake (Fig. 9) has a band 23 provided with a lining 22 and slung over a brake pulley 24 rigidly fixed to the axle 25 of the roll 2. The axle 25 rests in supports 26 to which one end of the brake band 23 is fixed at 27. To the other end of the brake band a rack 28 is fixed which is movable in the vertical direction in a guidance 15 29 in order to tighten or slacken the brake band.

20 With the rack 28 cooperates a toothed segment 30 turnable about a pin 31 fixed to the support 26 and arranged at the end of a two-armed lever to the other arm 32 of which a screw threaded spindle 33 is linked.

25 The pointed end 34 of the arm 19 (Figs. 3 and 4) is connected to the other part of the arm by means of an insulating piece 35 and is provided with a binding screw 36 to which a wire 37 is connected, above and 30 below the point 34 of the arm 19 contacts are arranged shown in detail in Figs. 7 and 8. Each contact comprises a contact pin in the form of a set screw 38 or 38' respectively adjustable in a metallic angular piece 39 35 mounted on a board 40. Each board is further provided with a binding screw 41 and 41' respectively to which the conduits 42 and 43 respectively are connected. The conduits 37, 42 and 43 lead to relays 44 and 40 45 respectively of the switches 44' and 45' respectively which are inserted in the supply mains leading to a three-phase electric motor 46. As may be seen from the diagram of 45 connections illustrated in Fig. 1 two phases of the current are exchanged in the switch 44' in comparison to the switch 45' so that when closing the latter the motor 46 rotates in one direction and when closing the switch 45' the motor rotates in the opposite direction.

On the shaft of the motor 46 a worm 47 (Figs. 5 and 6) is fixed which cooperates with a worm wheel 48 loosely mounted on a vertical shaft 49, the lower end of which has 55 a bore 50 provided with interior thread with which the spindle 33 cooperates. The shaft is mounted in a support 51 and is provided at its upper end with a knob 52 rigidly fixed thereto. Further on the shaft 49 and 60 secured against rotation by a feather 53 one half 54 of a claw clutch is displaceable, the teeth of the clutch cooperating with correspondingly shaped teeth formed in the nave of the worm wheel 48. When the clutch is 65 engaged the shaft 49 is turned in one or the

other direction by the motor 46 and the brake on the paper roll is tightened or slackened, when the clutch is disengaged the brake may be adjusted manually by turning the knob 52.

As soon as the tension in the web decreases the friction generated on the drum 10 decreases also, the sliding weight predominates, the arm 19 is lowered and its pointed end 34 bears on the lower contact pin 38, whereby a circuit through relays 45 and switch 45' is closed and the electric motor 46 is caused to rotate in such a direction that the brake on the paper roll is tightened; on the other hand when the tension of the web increases the friction action of the paper on the drum 10 predominates, the arm 19 is lifted to bear on the upper contact 80 38 and a circuit over relays 44 and switch 44' to the motor is closed, whereby the latter is rotated in a direction which causes a slackening of the brake on the paper roll. The actuation of the brake in one sense or the other lasts only for such a time until the original tension in the web has been re-established, whereupon the arm 19 returns into its mid-position and the circuit to the motor is again interrupted.

The above described arrangement is very sensitive and responds to the smallest variations in the tension of the web so that the tension may be practically maintained constant. As in this case no stretching or shrinkage of the web occurs the arrangement of the present invention causes a good register and the possibility of producing multi-color prints on rotary printing machines.

I claim:

1. An arrangement for automatically maintaining constant the tension in the web 105 of paper unwound from a roll of paper, comprising in combination, braking means adapted to act on the roll from which the web is unwound, a movably mounted device over which the web slides, means on said device adapted to counteract the friction action caused by the web sliding on said device, a controlling device influenced by said means on said device and including electric circuits, and an electric motor operating said 110 braking means and controlled by said controlling device.

2. An arrangement for automatically maintaining constant the tension in the web of paper unwound from a roll of paper, comprising in combination, braking means adapted to act on said roll of paper, a rotatably mounted drum over which the web slides, adjustable means on said device to counteract the friction action caused by the web sliding on said drum and adapted to hold said drum in a determined position for a determined tension of the web, a controlling device with which said adjustable means cooperate as soon as a variation in the ten- 125 130

sion of the web occurs, and an electric motor operating said braking means and controlled by said controlling device.

3. An arrangement for automatically 5 maintaining constant the tension in the web of paper unwound from a roll of paper, comprising in combination, braking means adapted to act on said roll of paper, a rotatably mounted drum over which the web 10 slides, an arm on said drum and a sliding weight on said arm for counteracting the friction caused by the web sliding on the drum and adapted to hold said drum in a determined position for a determined tension of the web, contacts with which said arm cooperates as soon as an alteration of the tension of the web occurs, an electric motor operating said braking means, and electric circuits interposed between said contacts and said electric motor and comprising switches and relays operated by said contacts, one of said circuits having the phases exchanged as compared with the other circuit for reversing the motor.
- 25 4. An arrangement for automatically maintaining constant the tension in the web

of paper unwound from a roll of paper, comprising in combination, braking means adapted to act on said roll of paper, a rotatably mounted drum over which the web 30 slides, an arm on said drum and a sliding weight on said arm for counteracting the friction caused by the web sliding on the drum and adapted to hold said drum in a determined position for a determined tension of the web, contacts with which said arm cooperates as soon as an alteration of the tension of the web occurs, an electric motor, transmission means interposed between said electric motor and said braking 40 means, a clutch interposed in said transmission means for cutting out the motor when said transmission have to be operated by hand, and electric circuits interposed between said contacts and said electric motor 45 and comprising switches and relays operated by said contacts, one of said circuits having the phases exchanged as compared with the other circuit for reversing the motor.

In testimony whereof, I have signed my 50 name to this specification.

FRIEDRICH FUCHS.
